UNITED STATES PATENT OFFICE.

SAMUEL W. SALMON, OF MINERAL POINT, WISCONSIN.

AUTOMATIC DRAFT-REGULATOR.

No. 867,839.

Specification of Letters Patent.

Patented Oct. 8, 1907.

Application filed April 7, 1906. Serial No. 310,540.

To all whom it may concern:

Be it known that I, SAMUEL W. SALMON, a citizen of the United States, residing at Mineral Point, in the county of Iowa and State of Wisconsin, have invented 5 a new and useful Automatic Draft-Regulator, of which the following is a specification.

The invention relates to an automatic draft regulator.

The object of the present invention is to improve the 10 construction of draft regulators designed for use on forced draft engines and boilers, and adapted to maintain automatically an even draft, whereby a saving in both fuel and water is effected.

A further object of the invention is to provide an 15 automatic draft regulator of this character, adapted to relieve the cylinder of back pressure, and capable, when a traction engine is passing between stacks, or other points where there is danger of fire, of enabling a smoke stack to be relieved of the entire exhaust, 20 whereby the engine is effectually prevented from throwing out any sparks.

With these and other objects in view, the invention consists in the construction and novel combination and arrangement of parts, hereinafter fully described, illustrated in the accompanying drawing, and pointed out in the claims, hereto appended; it being understood that various changes in the form, proportion, size and minor details of construction, within the scope of the 30 claims, may be resorted to without departing from the spirit or sacrificing any of the advantages of the invention.

The figure of the drawing is a sectional view of an automatic draft regulator constructed in accordance with this invention and shown applied to a boiler.

35 Referring to the drawing, 1 designates the exhaust pipe of a traction engine, but the improvements herein shown and described are applicable to all force feed engines and boilers. The exhaust pipe 1, which extends from the steam chest (not shown) to the smoke stack 2, 40 pierces the boiler 3 at one side thereof, and is provided at the base of the stack 2, with an upwardly projecting nozzle 4, from which the exhaust steam is discharged into the smoke stack to provide a force draft. The transverse portion 5 of the exhaust pipe is arranged 45 horizontally, and the discharge nozzle 4 extends upward therefrom at right angles thereto.

The exhaust pipe communicates at the angle formed by the nozzle and the transverse portion 5, with a relief pipe 6, a valve 7 being placed at the inner end of the 50 transverse portion at a point below the nozzle, in position to receive the full force of the exhaust steam. The valve 7 is provided at its lower edge with an eye 8, through which passes a pivot 9, on which the valve 7 swings. The transverse portion 5 is provided with an 55 extension 10, located beyond the discharge nozzle 4, and preferably extending to the opposite side of the boiler,

as shown. The extension 10 forms a casing for a rod 11, and is provided with a stop 12, consisting of a projection and arranged to limit the backward or outward swinging of the valve. When the valve is swung backward to the position illustrated in dotted lines in the figure of the drawing, the exhaust pipe is placed in communication with the relief pipe 6, which extends upward from the exhaust pipe. The upper portion 13 of the relief pipe is deflected laterally, and is extended 60 through the adjacent wall of the smoke stack, its discharge end being arranged exteriorly of the stack. When the valve is open, the exhaust steam passes through the transverse portion of the exhaust pipe and will impinge against the inclined valve and be deflected 65 into the relief pipe 6, from whence it will be discharged into the atmosphere. This will relieve the smoke stack entirely of the exhaust steam, and the engine will be effectually prevented from throwing out any sparks when the steam is escaping through the relief pipe. 70 This will be found advantageous when a traction engine is passing between stacks, or is passing any point where there is danger of fire.

The valve is provided at its outer or rear face with a centrally arranged eye 14, and is connected by a suitable pivot with the inner end of the rod 11. The rod 11 pierces the side of the boiler and extends exteriorly of the same. The outer portion of the rod receives a coiled spring 15, which serves to hold the valve yieldably in its closed position, and it will permit the valve 75 to open automatically when the pressure of the exhaust exceeds a predetermined point. The valve will thus permit a portion of the exhaust steam to escape through the relief pipe, and an even draft will be maintained, thereby effecting a saving in both fuel and water. The 80 inner end of the spring bears against a collar 16, or other suitable means carried by the rod 11, and the outer end of the spring engages an operating lever 17, fulcrumed at its lower end 18 on a suitable support 19, and adapted to be swung inwardly and outwardly to 85 open and close the valve 7, and to place the desired tension on the spring. The lever is provided at an intermediate point with an opening, through which the outer end of the rod 11 passes, and the outer end of the rod is threaded to receive a nut 11^a, a suitable washer 90 being provided between the nut and the lever, as shown. The support 19 consists of a bracket composed of upper and lower portions, the upper portion being provided with a curved series of teeth 20, adapted to be engaged by a spring actuated dog or detent 21, which 95 is carried by the operating lever. The operating lever is also provided adjacent to its grip or handle, with a latch lever 22, by means of which the spring actuated dog or detent is operated. The upper portion of the bracket is curved, and the teeth are arranged substantially in the arc of a circle. 100

The relief pipe and the valve may be arranged at dif-

ferent points between the steam chest and the discharge nozzle without affecting the result, but the valve, to be most effective, should be arranged in position to receive the full impact of the exhaust steam.

5 Having thus fully described my invention, what I claim as novel and desire to secure by Letters Patent, is:-

1. The combination with the exhaust pipe of a steam engine having a discharge nozzle opening into the stack, 10 of a relief pipe discharging exteriorly of the stack, a valve for establishing communication between the exhaust pipe and the relief pipe and for cutting out the latter, and means for yieldably holding the valve closed, said means being exteriorly adjustable and being provided with 15 exteriorly arranged operating mechanism for manually opening and closing the valve.

2. The combination of the exhaust pipe of a steam engine having a nozzle opening into the stack and provided with a horizontal transverse connecting portion and with 20 a horizontal extension located on the opposite side of the nozzle from the connecting portion, a valve mounted in the extension, a relief pipe communicating with the extension in rear of the valve when the latter is closed, said valve being adapted to open to establish communication between the relief pipe and the exhaust pipe, and 25 means for yieldably holding the valve closed, said means being exteriorly adjustable, whereby an even draft is maintained in the stack.

3. The combination of the exhaust pipe of a steam engine having a nozzle opening into the stack and provided 30 with a transverse connecting portion and with an extension located opposite the connecting portion, a valve mounted in the extension, a relief pipe communicating with the extension in rear of the valve when the latter is closed, said valve being adapted to open to establish communication between the relief pipe and the exhaust-pipe, 35 a rod connected with the valve, a spring disposed on the rod for holding the valve yieldably in its closed position, and operating mechanism connected with the rod for

manually opening the valve and also engaging the spring 40 for placing the same under tension.

4. The combination of the exhaust pipe of a steam engine having a nozzle opening into the stack and provided with a transverse connecting portion and with an extension located opposite the connecting portion, a valve 45 mounted in the extension, a relief pipe communicating with the extension in rear of the valve when the latter is closed, said valve being adapted to open to establish communication between the relief pipe and the exhaust-pipe, a rod connected with the valve, a spring disposed on the 50 rod for holding the valve yieldably in its closed position, an operating lever connected with the rod and engaging the spring, and means for securing the operating lever in its adjustment.

5. The combination with an exhaust pipe of a steam 55 engine, a relief pipe, a valve arranged between the relief pipe and the exhaust pipe for cutting off and controlling communication between the said pipes, a rod connected with the valve, a spring for yieldably holding the valve in its closed position, an operating lever connected with the 60 rod and engaging the spring, and means for securing the lever in its adjustment.

6. The combination with an exhaust pipe of a steam engine, a relief pipe, a valve arranged between the relief pipe and the exhaust pipe for cutting off and controlling 65 communication between the said pipes, a rod connected with the valve, a spring for yieldably holding the valve in its closed position, an operating lever connected with the rod and engaging the spring, a bracket supporting the lever and provided with a plurality of teeth, and means 70 carried by the lever for engaging the teeth to secure the lever in its adjustment.

In testimony, that I claim the foregoing as my own, I have hereto affixed my signature in the presence of two witnesses.

SAMUEL W. SALMON.
